UNITED STATES PATENT OFFICE.

THOMAS S. HOMANS, OF HEMPSTEAD, NEW YORK, ASSIGNOR TO INTERTYPE CORPORATION, OF BROOKLYN, NEW YORK, A CORPORATION OF NEW YORK.

MAGAZINE MOUNTING FOR TYPOGRAPHICAL MACHINES.

Application filed October 22, 1925. Serial No. 64,256.

The present invention relates to improvements in typographical machines of the class wherein matrices are delivered from a matrix magazine to an assembling point and composed into a line from which a type bar or slug is cast, after which the matrices are distributed and returned to the magazine; and it relates more particularly to machines of this class which are adapted to contain a plurality of magazines holding, respectively, matrices belonging to different fonts, the magazines having means for adjusting them whereby one or another of the magazines may be set in operative position to deliver matrices therefrom for assembly and to receive matrices which are distributed and returned thereto after a cast has been made from the matrix line.

A machine of this general class is shown and described in my prior Patent No. 1,352,965, granted Sept. 14, 1920, wherein are shown three separate magazine structures holding, respectively, one, two and three magazines, each of these structures comprising a unit which can be mounted interchangeably in a single main frame of standard form, thus enabling the machine to be assembled as a one, two or three magazine machine, or converted from a one or two magazine machine into one containing two or three magazines. However, in such magazines, each unit, which contains a number of magazines in superposed relation, comprises a primary frame or cradle and a secondary or magazine-supporting frame which carries the magazines, the primary frame or cradle carrying mechanism for shifting the secondary or magazine-supporting frame therein in a manner to bring one or another of the magazines into operative relation with the single assembler and distributor of the machine. Also, in such machines, each magazine unit, consisting of the primary frame or cradle, the secondary or magazine-supporting frame and the set of magazines, is tilttable from its normal or operative forwardly inclined position to a reversed or rearwardly inclined position for the removal or insertion of magazines, the cradle of each unit being provided for this purpose with pivots which engage bearings in the main frame.

The primary object of the present invention is to provide a simplified and improved structure whereby the tilting of the maga-

zine structure for the removal or interchange of a magazine and the return of the structure to bring one or another of the magazines into operative relation with the assembler and distributor can be accomplished by moving or rocking only the magazines and their supporting frames while the frame or structure on which the magazine-supporting frame is mounted and which carries the mechanism for shifting the magazines and their supporting frame remains stationary and thus may form part of, or be rigidly connected with, the main frame of the machine. In this way the weight of the structure to be lifted and rocked to bring the magazines into position for operation or removal and the requisite effort to be exerted to accomplish such lifting and rocking movements are considerably reduced, and other advantages are obtained in the manipulation and operation of the machine.

To these and other ends, the invention consists in certain improvements and combinations and arrangements of parts, all as will be more fully hereinafter described, the features of novelty being pointed out particularly in the claims at the end of the specification.

In the accompanying drawings:

Fig. 1 is a side elevation of a portion of a typographical machine of the class hereinbefore referred to, embodying magazine-supporting and positioning means constructed in accordance with the present invention, the magazines occupying their operative or normal forwardly inclined position.

Fig. 2 is a view similar to Fig. 1, the magazines however being shown tilted into a rearwardly inclined position for removal or replacement of one or more of the magazines.

Fig. 3 illustrates the structure shown in Fig. 1 as viewed from the right in said figure.

Fig. 4 is a detail view, partly in section, showing a portion of the mechanism for shifting the magazine-supporting frame to bring one or another of the magazines into position for operation and also showing a portion of the means which detachably connects the magazine-adjusting mechanism to the magazine-supporting frame.

Similar parts are designated by the same reference characters in the different figures.

The main frame of the machine, as is

usual in machines of this class, comprises, for convenience in manufacture, a number of components which may be made separately but are bolted or otherwise rigidly secured together.

In the present instance the numeral 1 designates a portion of the main frame of a typographical machine of the general class hereinbefore referred to, and 2 represents a portion of the distributor bracket which is bolted to, and forms a component of the main frame and serves to support the matrix distributor in a manner well known in the art. According to the present invention a pair of frame members 3, one at each side of the machine, are rigidly attached to the distributor bracket arms 2 or are otherwise constructed as rigid or immovable components of the main frame of the machine.

In the instance shown, three matrix magazines 4 are mounted on a magazine-supporting frame which comprise frame members 5 and end pieces 6, which rigidly unite them, the magazines and their supporting frame thus constituting a unit. This magazine unit is provided towards its upper end with a pair of alined rollers 7, which are journaled on pins 8 fixed to the magazine-supporting frame, and these rollers are arranged to overlie and ride upon tracks or latches 9, which are attached to and slidably mounted, as by the pin and slot devices 10, on the upper ends of the members 3. The magazine unit while in its forward or operative position is supported at its lower end by a shaft 11, which detachably receives or on which rest open bearings 12, preferably fixed to the forward end of one of the frame members 5, these bearings straddling the shaft 11 when the magazine unit is in its forward or operative position but being free to lift or disengage from the shaft 11 when the magazine unit is shifted into its rearwardly inclined position as shown in Fig. 2.

The means shown in the present instance for positioning the ends of the magazines in operative relation to the assembling and distributing mechanism comprises stub shafts 13, which are fixed to cranks 14, the latter being arranged at the inner sides of the frame members 3 and have the shaft 11 fixed thereto eccentrically of the stub shafts. The stub shafts extend outwardly through the frame members 3 through slots 15 therein, these slots determining the plane in which the stub shafts 13 may shift in a forward or rearward direction, and a toothed rack 16 is provided at the inner side of each frame member 3 so that it extends parallel to the respective slot 15. Each stub shaft 13 has a toothed pinion 17 fixed thereon and engaging in the respective rack 16, and means such as a crank 18 fixed to one of the stub shafts 13 at the outer side of the respective frame member 3 is provided for ro-

tating the stub shafts and thereby revolving the cranks 14 and shaft 11 on which the forward end of the magazine unit rests. By operating the crank handle 18 and thereby rotating the cranks 14 and shaft 11, the magazine unit is caused to rise or fall bodily as it describes three cycloids or arcs corresponding to the operative positions of the three magazines, and at the same time the stub shafts 13, by reason of the engagement of their pinions 17 with the racks 16, will travel longitudinally in the slots 15 to carry the escapements 19 at the forward end of one magazine out of operative position with the escapement actuating reeds 20 and bring the escapements of another magazine into operative relation with the reeds.

The mode of operation of the magazine-shifting mechanism is set forth in detail in my prior Patent No. 1,156,031, granted Oct. 5, 1915, but it may be here stated that each cycloidal or arcuate movement causes the magazines to first rise, then move forwardly or rearwardly according to which magazine is to be brought into use, and finally descend, whereby the escapements of the magazine which has been in use are first lifted out of operative relation with the reeds 20, then these escapements are carried out of a position above the reeds 20 and the escapements of the selected magazine are brought into a position above the reeds, and finally the escapements of the selected magazine are lowered into operative relation with the reeds. While the lower end of the magazine unit is thus moving, the rollers 7 which support the upper end thereof will ride upon the tracks or latches 9 on the upper ends of the frame members 3.

From the foregoing it will be understood that the mechanism which shifts the magazines to bring one or another thereof into operative position is carried by the frame members 3 which are fixed to, or form part of, the main frame of the machine, and that the magazine unit is detachably connected to the shaft 11 of the magazine-shifting mechanism by the forked or open bearing members 12.

According to the present invention the magazine unit is arranged to be reversed or turned from its front or operative position towards its rearwardly inclined position for the withdrawal or replacement of the magazines by pivoting the magazine unit on the main frame or the frame members 3 which form a part thereof. To this end pins or studs 21 are fixed to and project laterally from the opposite sides of one of the frame members 5, preferably the intermediate frame member which carries the middle magazine. These pins or studs are located intermediately of the ends of the magazine unit. When it is desired to reverse or rotate the magazine unit towards the rear of

the machine, or from the position shown in Fig. 1 to that shown in Fig. 2, the magazine unit, if it is not at the moment in its lowermost operative position as shown in Fig. 1, is brought to that position by operation of the crank handle 18 in the proper direction. During such operation the studs 21 will pass into open slots 22 formed in the frame members 3 and come to rest on the seats 23 in these slots. When the studs are so seated, the magazine unit is in position to be rotated or rocked rearwardly, and the unit will be free for rearward rotation or rocking as soon as the latches or tracks 9 are slid forwardly, or from the normal position shown in Fig. 1 to that shown in Fig. 2, as the latches or tracks 9 will then deprive the rollers 7 of their supports and these rollers will be free to descend while the upper end of the magazine unit swings rearwardly, the pins or studs 21 during this rearward swing of the magazine unit pivoting on their seats 23. As the magazine unit is swung into the rearwardly inclined position shown in Fig. 2, the forward end of the unit is detached from the magazine-shifting mechanism carried by the frame members 3 by the lifting of the open bearings 12 from the shaft 11 of the shifting mechanism.

When the magazine unit is rocked forward or returned from its rearwardly inclined position to its forward operative position as shown in Fig. 1, the bearings 12 come to rest on the shaft 11, thus re-establishing the operative relationship between the forward end of the magazine unit and the shifting mechanism, and by returning the latches or tracks 9 to their normal position as shown in Fig. 1, the rollers 7 will become supported, so that rearward swing of the magazine unit is prevented.

The pins or studs 21 engage in the slots 22 of the frame members 3 only when the magazine unit is in its lowermost position as shown by Fig. 1. When the crank handle 18 is operated in a direction to bring the middle magazine into operative relation with the reeds 20, the cycloidal or arcuate movement of the lower or forward end of the magazine unit will carry the pins or studs 21 out of the slots 22, thence forwardly and finally downwardly until these pins or studs assume the position indicated at 21^a, Fig. 1, and when the crank handle 18 is operated to bring the lowermost magazine into operative relation with the reeds 20, the cycloidal or arcuate movement of the magazine unit incident thereto will bring the pins or studs into the position indicated at 21^b, Fig. 1.

The magazine unit may be guided laterally between the frame members 3 while moving under the action of the shaft 11 by providing the shaft 11 with reduced portions 11',

which form shoulders 11² thereon and by forming the open bearings 12 so that they snugly fit upon the reduced portions 11' between the shoulders 11², as shown in Fig. 4. The magazine unit is guided between the frame members 3 while rocking about the pins or studs 21 by suitable bosses on the magazine-supporting frame which bear against the inner sides of the frame member 3.

According to the present invention, the mechanism which shifts the magazine unit to bring one or another of the magazines into operative position is mounted or supported on the stationary main frame or a frame fixed to or forming a part of the main frame of the machine, and the magazine unit carries pivots which have a traversing movement relatively to the main frame during the magazine shifting movements of the magazine unit so that they permit such movements to take place without interference. The magazine shifting mechanism has a detachable connection with the magazine unit whereby it rocks rearwardly or into magazine removing position without interference from the magazine shifting mechanism, and when it is desired to rock said unit into a rearwardly inclined or magazine removing position, the pivots bear on the relatively fixed supporting frame and provide an axis about which such rocking movements take place.

I claim as my invention:—

1. A typographical machine comprising a main frame, a magazine unit embodying a plurality of superposed magazines shiftable relatively to the main frame to bring one or another of the magazines into operative position and also rockable to carry the magazines into magazine removing position, and mechanism mounted on the main frame and operative to shift the magazine unit, said mechanism having a detachable connection with the magazine unit to permit rocking thereof into magazine removing position.

2. A typographical machine comprising a main frame, a magazine unit embodying a plurality of magazines shiftable relatively to the main frame to bring one or another of the magazines into operative position and also rockable to carry the magazines into magazine removing position, mechanism carried by the main frame and detachably cooperative with the magazine unit to shift the latter to bring the desired magazine into position for use and permitting detachment of the magazine unit therefrom when the latter is rocked into magazine removing position, and pivots carried by the magazine unit which have a traversing movement relatively to the main frame during the magazine shifting movements of said unit and

are arranged to bear on the frame and provide an axis about which the magazine unit may rock into magazine removing position.

3. A typographical machine comprising a main frame, a magazine unit embodying a plurality of superposed magazines movable into different operative positions, and means for pivotally mounting the magazine unit directly on a component of the main frame whereby it may be rocked into a magazine-removing position when the magazine unit occupies one of said operative positions.

4. A typographical machine comprising a main frame, a magazine unit containing a plurality of superposed magazines movable into different operative positions, and means for pivotally mounting the magazine unit on the main frame whereby it may be rocked into a magazine-removing position when the magazine unit occupies one of said operative positions and for relieving it of said pivotal mounting when moved to bring another magazine into operative position.

5. A typographical machine comprising a main frame, a magazine unit containing a plurality of superposed magazines and movable to bring one or another of such magazines into operative position and also movable to carry the magazines into position for removal, and mechanism for moving the magazine unit to bring one or another of the magazines into operative position, said mechanism being carried on the main frame and arranged to connect with and disconnect from the magazine unit as the latter is rocked into or out of operative position.

6. A typographical machine comprising a main frame, a magazine unit containing a plurality of superposed magazines, means on the main frame for moving the forward end of the said unit to bring one or another of the magazines into operative position, and tracks on the main frame and cooperative projections on the magazine unit for guiding and supporting the rear end of the latter during the movements of the forward end thereof.

7. A typographical machine comprising a main frame, a magazine unit containing a plurality of superposed magazines, means on the main frame for moving the forward end of said unit to bring one or another of the magazines into operative position, pivot bearing members arranged to cooperate, when the magazine unit occupies a predetermined position, to support said unit to rock into a magazine-removing position, and means for supporting the rear end of the magazine unit and controlling the rocking movement thereof.

8. A typographical machine comprising a main frame, a magazine unit containing a

plurality of superposed magazines, means supporting the forward end of the magazine unit and operative to bring one or another of the magazines into operative position, pivot bearing members cooperative, when the magazine unit occupies a predetermined position, to support the unit for rocking movement into a magazine-removing position, and means supporting the rear portion of said unit, said means being adjustable to release said unit and permit it to rock into magazine-removing position.

9. A typographical machine comprising a main frame, a magazine unit containing a plurality of superposed magazines, pivot pins carried by the magazine unit, means for moving said unit in cycloidal paths to bring one or another of the magazines into operative position, and pivot bearing members arranged to be engaged with said pivot pins by the cycloidal movement of the magazine unit whereby the latter will be supported to rock into a position for magazine removal.

10. A typographical machine comprising a main frame having seats thereon, a magazine unit containing a plurality of superposed magazines and movable to bring one or another of the magazines into operative position, and pivot pins on said unit movable into cooperation with said seats on the main frame to support the unit to rock into magazine-removing position.

11. A typographical machine comprising a main frame, a magazine unit embodying a plurality of superposed magazines, and means shiftably supporting said unit directly on a component of the main frame whereby one or another of the magazines may be brought into operative position and for pivotally supporting said unit directly on said component of the main frame whereby said unit may be rocked into a magazine removing position.

12. A typographical machine comprising a main frame, a magazine unit embodying a plurality of superposed matrix magazines, said unit being shiftable relatively to the main frame to bring one or another of the magazines into operative position and also rockable to carry the magazines into magazine-removing position, and an eccentric shaft mounted on a component of the main frame and operative to lift and lower the matrix-delivery end of the magazine unit, said end of the magazine unit being arranged to rest removably on said shaft to permit rocking of said unit into magazine-removing position.

In testimony whereof I have hereunto set my hand.

THOMAS S. HOMANS.
